Hocking Glass Corporation, Lancaster, Ohio

Filed Nov. 14, 1968, Ser. No. 14,466

Term of patent 14 years

Int. Cl. D7—01

U.S. Cl. D36—8

FIG. 1 is a front elevational view of a tumbler or similar article showing my new design;

FIG. 2 is a side elevational view thereof;

FIG. 3 is a developed plan view of the ornamentation;

FIG. 4 is an enlarged sectional view taken along line 4—4 of FIG. 1.

The characteristic feature of my design resides in the specific ornamentation as applied to a typical tumbler. I claim:

The ornamental design for a tumbler or similar article, substantially as shown and described.
